UNITED STATES PATENT OFFICE

ANTONI MUSZYNSKI, OF EASTHAMPTON, MASSACHUSETTS

DESIGN FOR AN OIL TANK PEDESTAL

Application filed September 26, 1932. Serial No. 45,069. Term of patent 14 years.

To all whom it may concern:

Be it known that I, ANTONI MUSZYNSKI, a citizen of the United States of America, residing at Easthampton, in the county of Hampshire and State of Massachusetts, have invented a new, original, and ornamental Design for an Oil Tank Pedestal, of which the following is a specification, reference being had to the accompanying drawing, forming part thereof:

Fig. 1 is an elevational view of the article, showing my new design.

Fig. 2 is a partial sectional view on the line 2—2 of Fig. 1.

Fig. 3 is a sectional view on the line 3—3 of Fig. 1, showing the groove in the upper portion, and

Fig. 4 is a sectional view on the line 4—4 of Fig. 1, showing the grooves in the lower portion of the pedestal.

I claim:

The ornamental design for an oil tank pedestal, as shown.

ANTONI MUSZYNSKI.
